US0D1065086S

(12) **United States Design Patent** (10) **Patent No.:** **US D1,065,086 S**
(45) **Date of Patent:** **** Mar. 4, 2025**

(54) **IGNITION DEVICE**

(71) Applicant: **Taizhou Yingtuo Arts and Crafts Co., Ltd.**, Taizhou (CN)

(72) Inventor: **Tianjiao Liu**, Taizhou (CN)

(73) Assignee: **Taizhou Yingtuo Arts and Crafts Co., Ltd.**, Taizhou (CN)

(**) Term: **15 Years**

(21) Appl. No.: **29/853,581**

(22) Filed: **Sep. 16, 2022**

(30) **Foreign Application Priority Data**

Sep. 6, 2022 (CN) 202230588469.7

(51) **LOC (15) Cl.** **13-03**

(52) **U.S. Cl.**

USPC **D13/126**

(58) **Field of Classification Search**

USPC ... D10/46, 47, 50, 65, 70, 71, 81, 100, 103; D13/118, 122, 126

CPC .. F02P 17/12; F02P 23/04; F02P 9/007; F02P 15/10; F02P 23/045; F02P 3/0442; F02P 2017/125; F02P 5/145

(57) **CLAIM**

The ornamental design for an ignition device, as shown and described.

DESCRIPTION

FIG. 1 is a perspective view of an ignition device, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line showing of the ignition device is for the purpose of illustrating article and forms no part of the claimed design.

1 Claim, 7 Drawing Sheets
